THERMOSTATIC SWITCH

Calvin J. Werner, Dayton, Ohio, assignor, by
mesne assignments, to General Motors Corpora-
tion, Detroit, Mich., a corporation of Dela-
ware

Application September 3, 1932, Serial No. 631,609

7 Claims. (Cl. 200—138)

This invention relates to a switch, and more particularly to a thermostatically controlled switch.

It is an object of this invention to provide a thermostatically controlled switch for controlling a circuit in response to temperature variations.

It is also an object of this invention to provide a thermostatically controlled switch that has means for making or breaking or making and breaking the contacts more rapidly than can be accomplished with the ordinary form of thermostatically controlled switches now in use.

Another object of this invention is to provide a switch that while embodying the above features has one or more adjustments for controlling the switch action.

Another object of this invention is to provide a switch that may be enclosed in a sealed housing for use with refrigerators and in places where moisture, dust or dirt is a detriment to the use of an unsealed switch.

Still another object of this invention is to provide a switch that while having the above advantage is simple in construction, durable, and has flexibility of design.

Further objects and advantages of the present invention will be apparent from the following description, reference being had to the accompanying drawings wherein a preferred embodiment of one form of the present invention is clearly shown.

In the drawings:

Fig. 1 shows a side view of one form of switch embodying the principle of the present invention.

Fig. 2 is a modification of the switch shown in Fig. 1.

Figs. 3, 4 and 5 show a switch embodying a modified form of the present invention and indicate different stages in the operation of the switch, some parts being shown in elevation and some in section.

Fig. 6 is a view of a modified form of switch embodying the present invention and is taken substantially in the direction of the arrows and on a line 6—6 of Fig. 7.

Fig. 7 is a sectional side view of the switch shown in Fig. 6 and is taken substantially in the direction of the arrows and on a line 7—7 of Fig. 6.

With particular reference to Fig. 1 a thermostatic member or bimetallic strip 10 is supported at one end by a support or bracket 12 by means of lugs 16 formed on the end of the bimetallic strip or thermostatic member 10 that project into

apertures 14 formed on the end of the support or bracket 12. A screw 18 is threaded thru an aperture 20 in the support of bracket 12 so as to bear against one side of the thermostatic member 10 and provide an adjustment therefor. The screw 18 has a lock nut 22 for locking it in position after it has been set. A contact 24 is mounted on the thermostatic member 10, and is in co-operative relation with a stationary contact 26 that is mounted on a contact carrying member 28. A magnetic member or armature 30 is secured to the free end of the thermostatic member 10, and a magnet 32 is so placed relative to the armature 30 that it tends to urge the contacts 24 and 26 together by exerting a force upon the armature 30.

With particular reference to Fig. 2, parts bearing reference numerals similar to those of Fig. 1 are similar and perform similar functions. In this modification, however, an electromagnet 34 having a core 34 and a coil 36 is used. One end of the coil 36 is connected to the stationary contact 26 thru the contact carrying member 28 and a lead 38. The other end of the coil 36 is provided with a suitable lead 40 for connection to the circuit controlled by the switch.

With particular reference to Figs. 3, 4 and 5, parts bearing reference numerals similar to those previously used are similar and perform similar functions. In this modification, a cup-shaped member 42 having threads 46 on its outer surface is threaded into an aperture 44 in the bracket or support 12. One end of the cup-shaped member 42 has a groove or slot 48 cut therein to facilitate turning the member in the support 12 when making adjustments. The inner surface of the cup-shaped member 42 is threaded part way to accommodate a threaded adjusting plug 50. The adjusting plug 50 has a slot 52 cut in one end to facilitate turning the plug for making adjustments. The other end of the cup-shaped member 42 has an aperture 54 therein for the accommodation of the pin 56.

One end of the pin 56 bears against one side of the thermostatic member 10, and the other end has a head 58 thereon that slidably fits into the cup-shaped member 42. A resilient member 60 is interposed between the head 58 of the pin 56 and one end of the plug 50 to urge the pin against the thermostatic member 10. A nut 62 is threaded onto the thread 46 of the cup-shaped member 42 to lock the member 42 in place after adjustments have been made.

With particular reference to Figs. 6 and 7, a disk of insulating material or insulating support 110

70 has on one side a cup-shaped member 72 and on the other side a flanged annular member 74, both of which are riveted thereon by means of rivets 76. The diaphragm 78 and a smaller cup-shaped member 80 that covers the diaphragm are secured to a flange 82 of the flanged annular member 74 by means of rivets 84. A magnet 86 is secured to the insulating support or disk 70, within the confines of the cup-shaped member 72, by means of rivets 88. A pin 90 having a head 92 on one end that rests against the mid-portion of the diaphragm 78 projects thru an aperture 94 in the insulating disk 70. A resilient member 96 intermediate the head 92 and the insulating disk 70 urges the head 92 against the diaphragm 78. A supporting member 98 has a curved portion 102 at one end that rests in an aperture 100 in the magnet 86. The other end of the supporting member 98 rests against the end of the pin 90 that projects thru the insulating disk 70. A bimetallic strip or thermostatic member 104, a curved metallic strip 106 and a connecting lug 108 are secured to the mid-portion of the supporting member 98 by means of a rivet 110. A resilient member 112 is insulated from the cup-shaped member 72 by an insulating member 114, and presses against the members secured together by the rivet 110 so as to urge the ends of the supporting member 98 against their respective rests. An insulator 116 is secured to the curved metallic strip 106 so that it rests against the end of the cup-shaped member 72 and serves as a rest and to insulate the curved metallic strip 106 from the cup-shaped member 72.

35 An armature or magnetic member 118 is secured to the free end of the thermostatic member 104 and magnetically associated with the ends of the magnet 86. An insulator 120 is secured to the thermostatic member 104 near its free end to prevent it from contacting with the cup-shaped member 72. A contact 122 is also secured to the thermostatic member 104 near the free end of that member, and so as to be aligned and make contact with a stationary contact 124. The stationary contact 124 is mounted on the end of a screw 126 that is threaded into a ring 128 and has a slot 130 cut in its other end to facilitate turning the screw, and making adjustments. The ring 128 is mounted in an aperture 136 in the insulating disk 70 and is secured therein by means of a shoulder 132 at one of its ends and a riveted or rolled edge 134 at its other ends. A connecting lug 138 interposed between the riveted or rolled edge 134 of the ring 128 and the insulating disk 70, and having one end of a lead 140 connected thereto, serves as a means for making an electrical connection to the stationary contact 124. The other end of the lead 140 is connected to the flanged annular member 74. A plug 142 is threaded into an aperture 144 in the flanged annular member 74 so as to cover and provide a means for gaining access to the slotted end of the screw 126. The washer 146 fits around the plug 142 and provides a tight joint or seal between the plug 142 and the flanged annular member 74. The screw 148 is threaded into an aperture 150 in the smaller cup-shaped member 80 so that its end may be forced against the mid-portion of the diaphragm 78 opposite the head 92 of the pin 90.

60 A nut 152 mounted on the screw 148 serves to lock the screw into position after it has been properly adjusted. Connection is made to the movable contact 122 thru the thermostatic member 104, connecting lug 108, a lead 154, a lug 156, a rivet 158 and a lug 160. The rivet 158 is insu-

lated from the cup-shaped member 72 by means of washers 164 and passes thru an aperture 162 in the member 72 to form a sealed connecting means.

In the operation of the switch in Fig. 1, the thermostatic member 10, under normal temperature conditions, is substantially straight. A change in temperature in one direction from normal then causes the thermostatic member 10 to tend to flex with the end supported by the support 12 as a fixed or anchored end and the screw 18 as a pivot or fulcrum. However, the pulling force of the magnet 32 upon the armature or magnetic member 30 transmits a resisting force to the free end of the thermostatic member that acts against the force developed by the thermostatic member. After the force developed by the thermostatic member increases sufficiently to pass the equilibrium point between the forces, motion of the armature 30 away from the magnet 32 begins, and since the force due to the magnetic pull varies approximately as the square of the distance moved while the force of the thermostatic member varies approximately as the first power of the distance moved, the motion will be more rapid after once beginning than if the thermostatic member acted alone to break the connections between the contacts 24 and 26. In the same manner, the magnetic force aids in bringing the contacts together and thus brings about quicker action when closing the circuit than if the thermostatic member acted alone in returning to its non-flexed position after opening the contact.

The operation of the switch shown in Fig. 2 is similar to that of the switch shown in Fig. 1, except that an electromagnet is used and the magnet coil 36 is connected in the circuit controlled by the contacts 24 and 26. Hence, the magnetic force will only be effective when the contacts are together and the circuit thru the coil 36 is closed. This provides for quicker breaking of the contacts substantially as explained for Fig. 1, except that when the circuit breaks, the magnetic force is substantially completely ineffective in restraining the action of the thermostatic member.

In the switch shown in Figs. 3, 4 and 5, Fig. 3 shows the normal position of the elements of the switch. As the temperature changes, the thermostatic member 10 flexes against the force of resilient member 60 and this forces the pin 56 into the cup-shaped member 42 until the thermostatic member 10 rests against the end of the cup-shaped member 42 as shown in Fig. 4. The end of the cup-shaped member 42 then acts as a fulcrum and the flexing force develops to overcome the magnetic force as previously explained for Fig. 1. However, after motion starts the urging force of the resilient member 60 aids the flexing force in separating the contacts, and the motion of the pin 56 serves to separate the contacts farther than would a fixed fulcrum such as that used on a switch on Fig. 1, and as indicated in Fig. 5. By turning the cup-shaped member 42 in its support, the height of the fixed fulcrum may be varied, and hence the distance that the thermostat must move to contact with the fulcrum may be changed. Then, the urging force of the resilient member 60 may be varied by turning the plug 50. The adjusting of the plug 50 varies the force that tends to urge the thermostatic member 10 away from the fulcrum formed by the cup-shaped member 42, and also varies the ad-

ditional force due to the resilient member 60 that aids in the separation of the contact.

With particular reference to Figs. 6 and 7, the thermostatic member 104 is mounted on a supporting member 98, which supporting member has one fixed support for its curved end 102 and an adjustable support for its other end formed by the pin 90. By turning the screw 148, it may be caused to flex the diaphragm 78 and thus move the pin 90 that is urged against the diaphragm by the action of the resilient member 96. Movement of the pin 90 varies the position of one end of the supporting member 98 and rotates that member about its curved end 102, which action is transmitted to the thermostatic member 104 to vary its normal position. The resilient member 112 urges the supporting member 98 against the magnet 86 and the pin 90, while the curved metallic strip 106 and the insulator 116 serve to steady the thermostatic member and prevent it from coming in contact with the cup-shaped member 72.

The stationary contact 124 may be adjusted toward or away from contact 122 that is mounted on the thermostatic member by removing the plug 142 and turning the screw 126. The adjustment of the stationary contact 124 varies the distance between the armature or magnetic member 118 and the ends of the magnet 86, and hence varies the force applied to the armature 118 by the magnet 86 when the contacts are closed. The closer the armature 118 is set to the ends of the magnet 86, the greater will be the necessary flexing force developed by the thermostatic member 104 to open or separate the contacts. The action and operation of this switch is similar to those previously explained. The housing formed by the cup-shaped member 72, the flanged annular member 74 and the smaller cup-shaped member 80 serves as a protection to prevent moisture, dust, dirt or grease from getting into the switch and impairing its action in any of its various adaptions.

While the form of embodiment of the present invention as herein disclosed constitutes a preferred form, it is to be understood that other forms might be adopted, all coming within the scope of the claims which follow.

What is claimed is as follows:

1. A switch, comprising in combination, a thermostatic member; means for supporting said thermostatic member so that it may flex in response to temperature change; cooperating contacts, one of which contacts is movable in response to the flexing of said thermostatic member; means for supporting the other of said contacts; adjusting means for adjusting the normal position of said thermostatic member; an armature attached to said thermostatic member; a magnet for applying a force to said armature; and a housing for said switch comprising, a cup-shaped member, a flanged annular member adjoining said cup-shaped member, a diaphragm, a smaller cup-shaped member placed over said diaphragm and secured to said flanged member, and means secured to said smaller cup-shaped member for actuating said adjusting means by flexing said diaphragm.
2. A switch, comprising in combination, a thermostatic member; means for supporting said thermostatic member so that it may flex in response to temperature change; cooperating contacts, one of which contacts is movable in response to the flexing of said thermostatic member; means for supporting the other of said contacts; adjusting means for adjusting the normal position of said thermostatic member; an armature attached to said thermostatic member; a magnet for applying a force to said armature; and a housing for said switch comprising, a cup-shaped member, a flanged annular member adjoining said cup-shaped member, a diaphragm, a smaller cup-shaped member placed over said diaphragm and secured to said flanged member, and means secured to said smaller cup-shaped member for actuating said adjusting means by flexing said diaphragm.

3. A switch comprising, in combination, a thermostatic member; means for supporting said thermostatic member so that it may flex in response to temperature change, said supporting means including a movable pivotally mounted member to which the thermostatic member is secured; cooperating contacts, one of which contacts is movably mounted so as to move in response to the flexing of said thermostatic member; means for supporting the other of said contacts; a housing providing an enclosure for the switch elements and comprising a substantially cup-shaped member, a flanged annular member adjoining said cup-shaped member, a diaphragm of flexible material secured to the flanged annular member to form a second substantially cup-shaped member therewith, a third substantially cup-shaped member covering said diaphragm; adjusting means extending thru the third cup-shaped member for flexing the diaphragm; and means intermediate the diaphragm and movable pivotally mounted member for adjusting the position of the movable pivotally mounted member in response to the diaphragm flexure caused by said adjusting means.
4. A switch comprising, in combination, a thermostatic member; means for supporting said thermostatic member so that it may flex in response to temperature change, said supporting means including a movable pivotally mounted member to which the thermostatic member is secured; cooperating contacts, one of which contacts is movably mounted so as to move in response to the flexing of said thermostatic member; means for supporting the other of said contacts; a housing providing an enclosure for the switch elements and comprising a substantially cup-shaped member, a flanged annular member adjoining said cup-shaped member, a diaphragm of flexible material secured to the flanged annular member to form a second substantially cup-shaped member therewith, a third substantially cup-shaped member covering said diaphragm; adjusting means extending thru the third cup-shaped member for flexing the diaphragm; and means intermediate the diaphragm and movable pivotally mounted member for adjusting the position of the movable pivotally mounted member in response to the diaphragm flexure caused by said adjusting means, said means intermediate the diaphragm and movable pivotally mounted member being resiliently urged against said diaphragm.
5. A switch comprising, in combination, a support member; a stationary contact adjustably mounted on the support member; a magnet secured to the support member and having its magnetic pole tips near the stationary contact; a thermostatic member having a contact mounted thereon that is engageable with said stationary contact, and an armature also mounted thereon and magnetically associated with said magnet; means comprising a movable member for supporting said thermostatic member so that it will flex in response to temperature change to

tacts; adjusting means for adjusting the normal position of said thermostatic member; and a housing for said switch comprising, a cup-shaped member, a flanged annular member adjoining said cup-shaped member, a diaphragm, a smaller cup-shaped member placed over said diaphragm and secured to said flanged member, and means secured to said smaller cup-shaped member for actuating said adjusting means by flexing said diaphragm.

3. A switch comprising, in combination, a thermostatic member; means for supporting said thermostatic member so that it may flex in response to temperature change, said supporting means including a movable pivotally mounted member to which the thermostatic member is secured; cooperating contacts, one of which contacts is movably mounted so as to move in response to the flexing of said thermostatic member; means for supporting the other of said contacts; a housing providing an enclosure for the switch elements and comprising a substantially cup-shaped member, a flanged annular member adjoining said cup-shaped member, a diaphragm of flexible material secured to the flanged annular member to form a second substantially cup-shaped member therewith, a third substantially cup-shaped member covering said diaphragm; adjusting means extending thru the third cup-shaped member for flexing the diaphragm; and means intermediate the diaphragm and movable pivotally mounted member for adjusting the position of the movable pivotally mounted member in response to the diaphragm flexure caused by said adjusting means.

4. A switch comprising, in combination, a thermostatic member; means for supporting said thermostatic member so that it may flex in response to temperature change, said supporting means including a movable pivotally mounted member to which the thermostatic member is secured; cooperating contacts, one of which contacts is movably mounted so as to move in response to the flexing of said thermostatic member; means for supporting the other of said contacts; a housing providing an enclosure for the switch elements and comprising a substantially cup-shaped member, a flanged annular member adjoining said cup-shaped member, a diaphragm of flexible material secured to the flanged annular member to form a second substantially cup-shaped member therewith, a third substantially cup-shaped member covering said diaphragm; adjusting means extending thru the third cup-shaped member for flexing the diaphragm; and means intermediate the diaphragm and movable pivotally mounted member for adjusting the position of the movable pivotally mounted member in response to the diaphragm flexure caused by said adjusting means, said means intermediate the diaphragm and movable pivotally mounted member being resiliently urged against said diaphragm.

5. A switch comprising, in combination, a support member; a stationary contact adjustably mounted on the support member; a magnet secured to the support member and having its magnetic pole tips near the stationary contact; a thermostatic member having a contact mounted thereon that is engageable with said stationary contact, and an armature also mounted thereon and magnetically associated with said magnet; means comprising a movable member for supporting said thermostatic member so that it will flex in response to temperature change to

- effect engagement or disengagement of the contacts; a substantially cup-shaped member secured to the support member and providing an enclosure over the magnet and thermostatic element; a flanged annular member secured to the opposite side of the support member from said cup-shaped member; a diaphragm of flexible material secured to the flanged annular member to form a second cup-shaped member therewith; a third substantially cup-shaped member covering said diaphragm; adjusting means extending thru the third cup-shaped member for flexing the diaphragm; and means intermediate the diaphragm and movable member for adjusting the position of the movable member in response to the diaphragm flexure effected by said adjusting means.
6. A switch comprising, in combination, a thermostatic member; means for supporting the thermostatic member so that it will flex in response to temperature change; cooperating contacts, one of which is movable in response to the flexing of said thermostatic member; means for supporting said contacts; resilient means urging against the thermostatic member; a stop cooperating with the resilient means and prevent-

ing flexure of the thermostatic member beyond a predetermined limit against the force of said resilient means, said stop acting as a fulcrum for further flexure of the thermostatic member in the same direction until the thermostatic member separates the contacts; said resilient means aiding in the separation of the contacts; and magnetic means tending to hold said contacts in engagement.

7. A switch comprising, in combination, a support member; a thermostatic member mounted at one end to the support member and having a first contact mounted near its other end, said thermostatic member being adapted to flex in response to temperature changes; a second contact engageable with the first contact; magnetic means tending to hold said contacts in engagement; means applying a force to the thermostatic member intermediate the ends thereof, which means resists flexure of the thermostatic member in one direction; a stop for limiting flexure of the thermostatic member against the means and providing a fulcrum for further flexure of the thermostatic member.
